UNITED STATES PATENT OFFICE.

FRIEDRICK BRITSCH, OF NEW YORK, N. Y., ASSIGNOR TO C. WEINBERG & CO., OF SAME PLACE.

DESIGN FOR GIMP.

SPECIFICATION forming part of Design No. 24,357, dated June 4, 1895.

Application filed May 6, 1895, Serial No. 548,343. Term of patent 7 years.

To all whom it may concern:

Be it known that I, FRIEDRICK BRITSCH, a citizen of the United States, residing at the city, county, and State of New York, have invented and produced a new and original Design for Gimp, of which the following is a specification, reference being had to the accompanying drawing, in which I have represented my design by an elevation.

10 The leading feature of my design consists of a series of raised figures with compound curved edges and tapering toward their ends and arranged diagonally to the respective edges of the gimp, so that the end of one 15 raised figure laps past the adjoining end of the next raised figure.

Groups of ornamental cords constitute the series of raised figures *a*, and said figures *a*

are arranged diagonally to the edges of the gimp and are tapering toward their ends; the 20 end of one figure laps past the adjoining end of the next raised figure, and said figures have compound curved edges and approximate a twisted rope in appearance.

The raised cords *b* are in groups adjacent 25 to the respective edges of the gimp.

What I claim is—

The design for gimp substantially as shown and described.

Signed by me this 3d day of May, A. D. 30 1895.

FRIEDRICK BRITSCH.
